UNITED STATES PATENT OFFICE.

CLAES ALBIN LINDBERG AND JOSEPH HINDLEY, OF NEW BEDFORD, MASSACHUSETTS.

STOP MECHANISM FOR COMBING-MACHINES.

1,265,794.

Specification of Letters Patent. Patented May 14, 1918.

Application filed June 7, 1917. Serial No. 173,266.

To all whom it may concern:

Be it known that we, CLAES ALBIN LINDBERG and JOSEPH HINDLEY, citizens of the United States, residing at New Bedford, in 5 the county of Bristol and State of Massachusetts, have invented certain new and useful Improvements in Stop Mechanism for Combing-Machines, of which the following is a specification.

10 This invention relates to a stop mechanism for fiber combing machines, and more particularly to that class of combing machines now broadly in use in which weight-pressed calendering rolls are provided to compress the combed fibers such as shown, 15 for instance, in U. S. patent to Deletette, No. 625,967 of May 30, 1899.

In the preparation of cotton, wool, and other fibers into a suitable condition for 20 conversion into fabrics, the fiber is fed by a proper mechanism onto combing rolls which brush the tufts of fiber out into a fleecy sheet or layer in which the fibers all line in a single direction, their ends overlapping. 25 This sheet of fiber, technically known as the lap, is fed from the combing rolls to calendering or piecing rolls which press the fibers closely together to permit of their further being drawn into a round, untwisted 30 strand called a sliver. The calendering rolls must be supported yieldingly to permit them to spread when the lap passes between them, and in order to give them the proper tension, weights, suspended from 35 chains, hold the rollers together. There is, however, a frequent tendency on the part of these chains to break while the machine is operating, and if the machine is not stopped immediately, the lap may be broken 40 and the machine injured, causing waste of time and material.

The object of the present invention is to provide a stop mechanism which shall automatically operate to render the machine in- 45 active immediately upon the breaking of one or more of said chains.

This object is attained by a simple de- 50 vice readily applicable to standard machines, and comprises a unique way of connecting the weights with a belt shifting member by means of a chain, or other flexi-

ble connector, so that should a weight drop from its proper position the tension on the chain would release a detent, allowing a spring to operate a belt shifting mechanism. 55

In the accompanying drawings:

Figure 1 is a somewhat diagrammatic side view of a combing machine embodying my invention;

Fig. 2 is a section through part of the machine, showing the spring for operating the belt shifter;

Fig. 3 represents a diagrammatic section through the machine;

Fig. 4 shows in perspective how the automatic shifter connects with the usual shift rod on a combing machine;

Fig. 5 shows the trip mechanism to be operated when a weight falls;

Fig. 6 shows a top plan of the trip shown 70 in Fig. 5.

1 represents diagrammatically the main frame of a combing machine in which there are one or more—usually from four to eight—combing heads 2. Each combing head 2 is provided, in addition to combing mechanism (not shown) with feed rolls 3 and 4, known as detaching rolls, and calendering or piecing rolls 5 and 6 or any suitable clutch mechanism. The lower calendering roll 5 is rigidly supported in a rocking frame 7 in the frame 1. The upper calendering roll 6 is yieldingly supported in any manner known in this class of machines for the purpose of allowing the rolls 85 to spread when the lap 8, coming from the combing mechanism passes between them. In order to provide the proper tension to compress the lap an arm 9, pivoted at 10 and bearing downwardly on the ends of the 90 roll 6, is provided at each end of the combing head. Suspended from the arms 9 by means of chains 11 and bails 12 are weights 13, one weight with two chains preferably being suspended from each combing head. 95

All the combing heads 2, in a single frame 1, are driven from a single shaft 14 provided with a driving pulley 15 and a loose pulley 16. The pulleys are driven by a belt 17 connected with a suitable source 100 of power. Pivoted to the frame 1 is a belt shifting lever 18 provided with a belt en-

gaging member 19. Fulcrumed to the lever 18 is a rod 20, usually provided on machines of this class, running the whole length of the frame 1 and slidably supported in bearings 21 on said frame.

The rod 20 is provided with a downwardly projecting arm 22 which may be adjustable on said rod. Engaging the arm 22 is a curved arm 23 adjustably mounted 10 on the rotatable, vertical shaft 24 near the end of the frame 1. The upper end of the shaft 24 is supported in a bearing 25 and the lower end in the bearing block 26. Rigidly mounted on the shaft 24 at any convenient point is an arm 27, the outer extremity of which is connected to one end of a spring 28, the other end of the spring being secured to the frame 1. Ordinarily the arm 27 is so positioned that the spring 28 20 is kept under considerable tension.

Keyed to the lower end of the shaft 24, adjacent the bearing block 26, is a dog 29, provided with a shoulder 30. A pawl 31, provided with a similar shoulder 32, for 25 engaging the dog 29, is pivoted on the bearing block 26. This pawl and dog serve as a detent to normally hold the shaft 24 from rotation against the tension of spring 28.

Pivoted to the side of the bearing block 30 26, at 33, is a crank 34 having its arm 35 provided with a weight 36. The crank is provided with an eye 37 to which is connected a chain, or other suitable connector, 38, passing through eyes 39 on the weights 35 43 and connected to the frame 1 by a suitable bolt 40. The bolt 40 may be of such a nature as to provide for tightening or loosening the chain to obtain a proper adjustment. The upright portion of the crank 40 34 is adapted to engage and swing the projecting pawl 31 to release the dog 29 when the tension on the chain overbalances the weight 36.

During the operation of the machine, 45 should one or more of the chains 11 break, permitting any of the weights 13 to drop at either or both ends, the tension on the chain 38 will increase, drawing over the crank 34, thereby releasing the detent by 50 disengaging the pawl 31 from the dog 29, allowing spring 28 to rotate shaft 24 by means of arm 27 in the direction of the arrow in Fig. 4. The rotation of the shaft 24 will cause the curved arm 23 to push 55 arm 22 toward the frame 1, sliding the rod 20 in the same direction, thereby operating the lever 18 to shift the belt 17 to the loose pulley 16, causing the machine to stop.

Inasmuch as changes may be made in the 60 structural embodiment of my invention within the scope of the appended claims, it is intended that the accompanying drawings shall be considered as illustrative of a

preferred form rather than in a limiting sense.

We claim as our invention:

1. The combination with a roll and its driving means of a tensioning weight and means automatically controlled by displacement of said tensioning weight for moving 7 said driving means to inoperative position.

2. In combination with a combing machine having a piecing roll of a tensioning weight for the roll, and an automatic stop actuated by displacement of said weight for 7 moving said driving means to inoperative position.

3. The combination of a piecing roll having a driving means of a tensioning device connected with the roll for holding the roll 8 in normal position, and means controlled by the tensioning device for moving said driving means to inoperative position.

4. In a combing machine the combination with a piecing roll having a tensioning weight and a belt for driving said roll, of an automatic stop comprising a normally inoperative belt-shifting means for throwing the said driving belt out of operative relation with said roll, and means connecting said tensioning weight with said belt-shifting means for operating said belt-shifting means by the displacement of the tensioning weight.

5. In a combing machine, the combination 95 with a roll having a tensioning weight and a belt for driving the roll, of an automatic stop comprising a mechanism for shifting said belt out of operative relation with said roll, a spring normally tending to operate 10 said belt-shifting mechanism, means for holding said spring against operation, and a means operable upon the displacement of said weight for releasing said spring.

6. An automatic stop mechanism for a 10 belt-driven piecing roll provided with a tensioning weight, comprising a spring-actuated belt-shifting mechanism having a detent for holding it against operation, and a chain connecting said detent with said 110 weight for releasing the detent upon displacement of the weight.

7. An automatic stop-motion for combing machines provided with piecing rolls and tensioning weights therefor, comprising a 115 belt-shifting lever, a sliding rod running the length of the combing machine frame and connected with said lever, an arm on said rod, a spring rotated shaft provided with a projection for engaging said arm, a 120 detent for normally holding said shaft from rotation, and a chain connecting the combing machine weights with said detent for releasing the detent upon displacement of the weight.

8. An automatic stop for combing ma-

chines having a plurality of piecing rolls and tensioning weights therefor comprising a spring operated belt-shifter, a detent for holding it against operation, a chain communicating with all the tensioning weights on said combing machine and connected with said detent, and means on said detent for holding said chain normally under ten-

sion, said tensioning means being adapted to release the detent upon the displacement 10 of any of said weights.

In testimony whereof, we have hereunto subscribed our names.

CLAES ALBIN LINDBERG.
JOSEPH HINDLEY.
